PAVING MACHINE

Alvin C. Rasmussen, Indianapolis, Ind.

Application October 8, 1932, Serial No. 636,897

15 Claims. (Cl. 94—44)

In street and highway construction, it is customary of course to lay the surfacing material of the street or highway on a suitably prepared subgrade, the surfacing material being then leveled and finished off, usually in separate operations. Similar steps are required in the resurfacing or repairing of streets and highways already laid, so that a firm smooth surface, as free from irregularities as possible, will result.

10 The operations of spreading the surfacing materials, of leveling such spread materials to the proper grade, and the finishing off of the surface of the spread and leveled materials has heretofore required three successive and distinct 15 operations. The present invention provides a machine which will substantially simultaneously spread, level, and finish preparatory to rolling or tamping the road surfacing materials, thereby effecting a very substantial saving in the 20 amount of time required for operations of this character. The machine is adapted to handle road surfacing materials such as sand, gravel, bituminous material and concrete, either on new subgrades or on old roadways on which a new 25 wearing surface is to be placed; and the machine is equipped with instrumentalities whereby bridging of irregularities in the road surface by the material in question is prevented, these instrumentalities serving to thoroughly agitate 30 the surfacing materials as they are laid on to their foundation, while simultaneously filling in voids which might otherwise be left in the body of the roadway,

35 The machine of the present invention embraces a construction which, as has been said above, will effect a spreading, a leveling and a finishing of the road surfacing materials in substantially one operation. To this end the machine embraces a portable frame mounted on 40 suitable traction devices which are adapted either to run over the surface of the roadway, or to utilize the usual road forms as tracks for rails upon which the traction devices are adapted to operate. To this end the traction devices 45 conveniently take the form of wheels or rollers adapted to be fitted with demountable flanges which are used in places where the machine is desired to utilize longitudinal road forms as track rails upon which to travel.

50 To spread the material upon the foundation which, it is understood, will be either a newly prepared subgrade or a properly prepared, previously laid roadway, there is provided a spreading hopper which has an open bottom running 55 entirely the width of the hopper. This hopper

forms one of the principal features of this invention, since it constitutes not only the material spreading device but also includes the leveling and finishing instrumentalities for the concrete which is being laid upon the prepared 60 surface. It will be understood that the term "concrete" as herein employed refers not only to concrete aggregates as commonly defined in this road building art, but also to materials such as sand, gravel and bituminous materials, as 65 all such materials can be handled by the machine in similar fashion.

Since the hopper is to perform at least three coordinating functions it must be provided with suitable instrumentalities for imparting the desired operation upon the material being laid. 70 The hopper has an interiorly operating spiral or screw conveyor for evenly spreading the material therethrough, and has positioned therebeneath along the front edge of the hopper a 75 strike-off blade which facilitates the distribution of the material flowing from the hopper on to the surface to be covered. In view of the fact that the machine is adapted for reciprocatory travel along the roadway, to accomplish suitable 80 action upon the deposited material when the direction of travel of the machine is reversed, this strike-off blade serves to permit only sufficient material to flow out of the hopper as is required to bring the new surface to the desired 85 grade. After the machine has traveled back to a certain distance, it automatically reverses the direction of travel, and then on the forward travel, a blade provided along the back side of the hopper opening will scrape excess 90 material forward.

The arrangement of the hopper constitutes also an important feature of the invention. The hopper is mounted so that it will tip back and forth as the machine reverses the direction of travel. This may be accomplished in one instance by mounting the hopper on the same shaft on which the front supporting wheels are carried, the hopper being so arranged that when it is in a vertical position both the front and rear strike-off blades are approximately about one inch above the finished level. By means of the necessary mechanism the hopper is automatically tipped backwards so that the rear strike-off 95 blade is carried at the desired strike-off level, 100 at which time the forward strike-off blade will be approximately two inches higher; this will prevent the carrying forward of any slight excess of surfacing material ahead of the forward blade, a feature which is of importance as 105 110

it will be apparent that during the backward travel of the machine, if excess material be carried ahead of the back blade, this material would be left on the surface of the roadway when 5 the machine travels forward, thereby producing lateral ridges in the surface of the finished roadway. This tilting of the hopper and the provision of the strike-off blades accomplishes the desired leveling and finishing action on the 10 surface material virtually simultaneously with the spreading of the material on the foundation. Mechanism is of course provided for timing the tilting of the hopper with the reversal of the direction of travel of the machine. All of the 15 details of these constructions will be clarified in the description as it hereinafter proceeds.

In order to prevent any depressions or irregularities in the foundation to be bridged over by the surfacing materials as they are laid, it is 20 desirable to provide a plurality of harrow teeth on the forward cutting edge so that they provide a raking of the material in addition to the scraping produced by the strike-off blades by means of which the surfacing materials are 25 thoroughly broken up as they are laid; in this way a very efficient compacting leveling and finishing action may be obtained.

Furthermore, to facilitate the spreading of the 30 materials the hopper is desirably provided with a leveling screw or conveyor, which may be actuated as desired in either direction longitudinally of the hopper to correspondingly convey the materials desired through the hopper for uniform spreading of the material along the road 35 foundation. Edge blades are provided to prevent flow of aggregates from the ends of the hopper over the road forms or runway.

The invention may take several forms, two 40 of which are illustrated in the accompanying drawings.

In the drawings,

Figure 1 represents a side elevation of one form of machine embracing the principles of the present invention.

Figure 2 is a fragmentary plan view of the 45 machine shown in Fig. 1, and illustrating certain of the driving and control instrumentalities.

Figure 3 is a fragmentary view illustrating further details of the driving mechanism included 50 in the form of the invention shown in Fig. 2.

Figure 4 is a side elevation of a cam member employed to oscillate the hopper in the manner previously indicated.

Figure 5 is a plan view of the cam member 55 of Fig. 4.

Figure 6 is an end view of the cam of Fig. 4, the view being taken at right angles of Fig. 4.

Fig. 7 is a side elevation of a somewhat different 60 type of machine to that illustrated in Fig. 1, but embracing similar principles of the invention;

Fig. 8 is a fragmentary plan view of the driving instrumentalities employed in the modification of Fig. 7;

Fig. 9 is a side elevation, partially in section, of one of the supporting wheels or traction devices for the machine, illustrating the detachable flange therefor, as previously mentioned;

Fig. 10 represents a vertical sectional view of 70 an adjustable bearing which may be employed in either type of machine, illustrated in Figs. 1 and 7, whereby the height of the leveling and finishing instrumentalities may be adjusted relatively to the roadway surface, the view being

taken approximately on the line 10—10 of Fig. 11; and

Fig. 11 is an elevation of the bearing of Fig. 10, showing the adjusting mechanism thereof, the view being taken at right angles of Fig. 10.

Fig. 12 is a view, partially in section and partially in elevation, of the construction and mounting of the edge blades for preventing flow of aggregates from the ends of the hopper over the road forms, and

Fig. 13 is a plan view of this structure, taken on the line 13—13 of Figure 12.

Fig. 14 is a partial view of the forward strike off blade, showing the harrow teeth.

As has been previously indicated, the drawings illustrate two different forms of the invention although it will be apparent that other modifications may be made without departing from the spirit of the invention. Referring first to the form of machine illustrated particularly in Figs. 1, 2, and 3, it will be observed that the machine comprises an engine A, traction devices B and a hopper C, all of which are operatively mounted upon the frame D of the machine.

The engine A is of the usual type of internal combustion engine, and needs no particular description as it is of entirely standard construction.

The traction devices B, and the remaining mechanism to be hereinafter described in detail are all driven from the engine A through suitable drive instrumentalities which will be described in greater detail hereinafter. The traction devices B are in the form of wheels or rollers adapted to travel either on the surface of the roadway or upon the road forms usually provided where new roadway construction is being laid.

To this end the traction devices B are, in each instance, provided with a detachable flange 1, which is secured in position by removable bolts 2, so that when desired to run the machine along

the road forms, the flanges 1 may be bolted in position, by the bolts 2, which may be removed whenever it may be desired to run the machine over the roadway surface itself. The traction devices are mounted upon suitable shafts 3, which are driven by suitable driving means which will be described in detail hereinafter.

The hopper C is a distributing hopper for the materials being used for surfacing the roadway. These materials which may be sand, gravel, 125 bituminous materials, or concrete aggregates, or any equivalent road surfacing materials, are charged into this hopper C which has an open bottom and which is disposed at a suitable distance above the surface of the roadway. This

hopper is mounted upon a shaft 4, illustrated in Figs. 1 and 2 as being positioned in the frame of the machine midway between the traction devices B.

It is from this hopper that the materials are spread upon the roadway. For this purpose and to accomplish uniform spreading

action, there is provided within the hopper the spiral conveyor 5 which acts as a distributing screw for the materials. This screw 5 is mounted also on the shaft 4.

It has been indicated above that the hopper C not only spreads the material, but serves also to level the spread materials and to act upon them in such manner as to prevent bridging of the materials over depressions and other irregularities in the roadway surface, to thereby assure a uniform and solid layer of spread material. To accomplish this purpose, the hopper is provided with the depending strike-off blades 7 and 6 along the forward and rear edges of the

open bottom of the hopper; and as previously indicated, the forward blade 7 may be provided with harrow teeth 7a for working the materials laid by the machine.

5 In order to efficiently level and finish the surface of the roadway, this hopper C is provided with mechanism for tilting back and forth on the shaft 4 in timed relation with the automatic reversal of direction of travel of the machine 10 over the roadway. This brings us therefore to the consideration of the power transmission and driving mechanism for the various elements of the machine. It will be observed that suitably mounted on the frame D of the machine is a 15 shaft 8, carrying two clutch coupled stub ends 8a and 8b, and beneath this shaft and operated therefrom is a shaft 9 which drives the traction devices B over suitably power transmitting means. Suitably disposed between the shaft 8 20 and the engine A is a third shaft 10.

The engine A is provided with a clutch 11 of desired standard construction, which clutch may be referred to as the main clutch, and is also provided with reduction gearing 12 for suitably 25 reducing the speed of rotation of the mechanism. A sprocket illustrated for purposes of strength as a double sprocket 13, is directly driven by engine A; and power is transmitted from the sprocket 13, over sprocket chains, or equivalent 30 power transmitting instrumentalities 14 to a sprocket 15 mounted on the shaft 8. The stub end shafts 8a and 8b, aforesaid, are concentric with shaft 8, the outer ends of the stub shafts being mounted in the frame of the machine, as 35 will be apparent from Figure 2, for example, the inner ends of the stub shafts being supported in clutch devices as will be hereinafter more specifically explained, by means of which clutch devices the stub shafts are rendered independently 40 operable, being aligned with the shaft 8 by means of suitable pilot bearings mounted inside of the respective clutch structure. This being a standard and commonly used construction, it is not illustrated in the drawings.

45 It has been indicated before that there is positioned interiorly of the hopper C a spiral conveyor 5. This conveyor preferably acts only after the hopper has been charged with aggregates from a truck or equivalent charging device, and serves to distribute excess material and to 50 level out the material within the hopper. To this end, the conveyor screw is located above the bottom of the hopper, rather than at the bottom thereof.

55 For actuating this conveyor 5, there is provided a sprocket 16 adjacent the outer end of the stub shaft 8a, over which sprocket passes the sprocket chain 17 for driving a sprocket 18 mounted on the shaft 4 of conveyor 5. This arrangement therefore transmits power to the shaft 4 to rotate the conveyor 5 in one direction. It sometimes happens however, that the materials being distributed collect in excessive quantities 60 adjacent one end of the hopper during the spreading action, so that it is desirable to provide means for reversing the direction of rotation of the conveyor when such excess accumulates, so that the materials may be brought back by the conveyor and readily discharged in a uniform manner. For this purpose, the stub shaft 8b is provided at its outer end with a pinion 19 65 meshing with the gear 20 on the stub shaft 21, which stub shaft is provided with a sprocket 22 over which passes the sprocket chain 23, to

drive the sprocket 24' mounted on the other end of conveyor shaft 4.

In order that the pinion 19 does not drive continuously and simultaneously with the sprocket chain 17, and in order to independently actuate the stub shafts 8a and 8b for actuating the conveyor 5 as aforesaid, there are provided the clutches 23 and 24, in which are mounted, respectively, the inner ends of the stub shafts 8a and 8b, as has been mentioned above. Actuation of sprockets 16 and 22 is accomplished therefore by the selective actuation of these clutches 23 and 24, in a manner which will be apparent.

It has been mentioned also previously that when the machine has traveled in a certain distance in one direction, it automatically reverses its direction of travel, and that the distributing hopper is mounted so that it will tip back and forth as the machine reverses the direction of travel. The mechanism enabling this tipping movement of the hopper to take place will now be described.

It will be noted that the shaft 8 is provided with a sprocket 25, which drives the sprocket 26 mounted on the shaft 10. The shaft 10 carries the instrumentalities enabling the hopper to tip to thereby cause the reverse traveling of the machine, while holding the hopper against tipping during the said reverse travel; while then releasing the hopper for opposite tilting motion with again a corresponding reversal of travel of the machine. The aforesaid instrumentalities include a positioning cam 27 located at each end of shaft 10, and mounted for rotation with this shaft. These cams 27 may be desirably though not necessarily, of the shape shown well in Figure 4, and they engage during their course of rotation, a pair of rollers 28 and 28a, which are mounted upon the arm 29 provided with a slot 30, allowing the arm to oscillate back and forth, on the bearing 31. As the machine travels along the roadway, and actually is scraping the material laid on the road surface, then due to the friction or to the dragging of the hopper with its rake-off blades and its teeth upon the laid aggregates there is always a tendency for the hopper to be rotated or tilted in the opposite position from the one which is proper for that direction of travel. However, the configuration 100 of the cams 27 is such that this tendency is resisted by the engagement of the rollers 28 and 28a until the cams have rotated in such position that the rollers riding in engagement with the cam peripheries reach the point where the arm 105 29 yields under the tilting tendency of the hopper to release the hopper for tilting movement. This action is repeated upon reverse movement of the machine, and the hopper C will tilt back and forth in predetermined time intervals. It 110 is to be understood that the shape of the cams may be changed to vary the tilting action of the hopper.

As has been indicated previously, it is desirable, in order to accomplish a thorough finishing and leveling action, that the machine automatically reverses its direction of travel substantially coincidentally with the oscillations of the hopper. It will be recalled that it has already been said that the shaft 9 drives the 115 traction devices B, and in order to accomplish the desired reversal direction of travel of the machine, there are provided driving instrumentalities interconnecting the shaft 8 with the shaft 9, which driving instrumentalities include 120

a reversing mechanism actuated by the reciprocation of the hopper. These driving instrumentalities include a sprocket 33 mounted on shaft 8, which drives a corresponding sprocket 34 on shaft 9 by virtue of the sprocket chain or equivalent device 35. The driving instrumentalities also include a gear 36 on the shaft 8, meshing with the gear 37 on shaft 9. When gears 36 and 37 are operated obviously shaft 9 will be rotated in a direction opposite to the direction of rotation of the shaft 8; whereas when the sprockets 33 and 34 are actuated, the shaft 9 will be driven in the same direction as shaft 8. Therefore in order to obtain the proper direction of rotation of the shaft 9, instrumentalities must be provided whereby the sprockets or the gears may be selectively operated. For this purpose there is provided the double clutch mechanism 38, which consists of a pair of expanding clutches 39 and 40 selectively actuated by the arm 41 through the bell crank 42 to which is connected the lever 43, which is secured in turn to the hopper C. Therefore as the hopper oscillates, the arm 43 actuates the bell crank 42, which in turn actuates the arm 41 throwing the double clutch element of the clutch mechanism 38 either to one side or the other, thereby alternately engaging clutch 39 and clutch 40. By means of this arrangement, the driving sprocket 33 and the gear 36 are alternately operated so as to rotate the shaft 9 alternately in opposite directions. It will be understood that the driving gear 36 on the shaft 8 is of the same size as the driven gear 37 on the shaft 9, so that when the gear 36 is clutched, shaft 9 rotates at the same speed as shaft 8, so that the machine will travel in the corresponding direction a distance corresponding to the time interval between the shifting of the clutch member 38. However, the sprocket 33 is slightly smaller than the sprocket 34 so that when the driving sprocket 33 is clutched shaft 9 rotates at a slower speed than shaft 8, and in the same time interval as required for travel in the aforesaid direction, the machine will not travel oppositely as far. In this way the gradual forward travel of the machine is accomplished. It will be understood that when sprocket 33 is clutched, gear 36 is idle and when gear 36 is clutched, sprocket 33 is idle.

It will therefore be seen that as the machine gradually progresses along the roadway, efficient spreading, leveling and finishing actions are obtained in a substantially simultaneous manner, and the actuation of the various mechanisms is at all times under close control of an operator through the instrumentalities of the various clutch mechanisms described above, which are in turn controlled by suitable levers, as indicated in Fig. 1. In this figure lever 44 represents the control lever for the main clutch 11; lever 45 represents the control lever for the forward rotation of the distributing screw; lever 46 is the lever for reversing the direction of the rotation of the distributing screw, and lever 47 represents the lever for the control of the cam clutch 23a.

The form of the invention just described possesses among other advantages, that of having the distributing hopper supported substantially midway of the front and rear traction devices. This means as the traction devices are raised, due to going over a hump which might exist either in the forms or on the surface

of the roadway, the dressing edges of this hopper will only be raised or lowered one-half the distance that either the front wheels or the rear wheels may be raised or lowered.

In the modification of the construction illustrated in Figs. 7 and 8 there is illustrated a somewhat simpler form of the machine, although the principal features of the invention are the same as in the type already described. It will be seen from Figs. 7 and 8 that the distributing hopper is mounted between the front traction devices rather than at a point midway between the front and rear traction devices, as in the form of the machine just described. In Figs. 7 and 8, A' represents the engine, B' the traction devices, and C' the hopper. These parts are constructed entirely similar to the corresponding parts A, B, and C previously described. In the form of Figs. 7 and 8, however, the hopper C' is mounted on the shaft 3a upon which shaft 9 are mounted the forward traction devices. Otherwise the construction of the hopper C' is the same as that of the hopper C.

In this modified form of the machine, the engine A' is provided with power transmitting instrumentalities including a main clutch 11a and suitable reduction gears 12a, operating a sprocket drive 13a which in turn, through the medium of a sprocket chain 14a, drives the sprocket 15a, thence rotating the shaft 8c. This shaft 8c is provided with a sprocket drive 25a from which the sprocket 26a on the shaft 10a is driven. Mounted above the shaft 10a is a stub shaft 48, upon which are mounted the sprockets 49 for actuating the cam 27a, which is also mounted on shaft 48, it being understood that this structure is duplicated on the other side of the machine, two cams for the operation of the hopper being desirable.

Mounted upon the shaft 10a is the gear 37a adapted to mesh with the gear 36a on the shaft 8a.

By means of the sprockets 25a and 26a, the shafts 8c and 10a are rotated in the same direction, whereas through the instrumentality of the gears 36a and 37a, rotation in opposite directions will be accomplished. This action has already been described in connection with the previously described modification of the machine, and the action in the present case is the same as above.

Actuation of the sprocket and gear on shaft 10a is accomplished by the provision of the double clutch element 38a on shaft 8c, this clutch element being composed of the corresponding clutches 39a and 40a engageable by a shiftable clutch cone actuated by the bell crank 42a, which is in turn actuated by the lever arm 43a secured suitably to the hopper C'. When the hopper C' is rocked, clutches 39a and 40a will be alternately engaged and disengaged so that the machine will travel back and forth over the roadway in timed relation with the rocking of the hopper; and since the gears 36a and 37a are of the same size, and the sprocket 25a is slightly smaller than the sprocket 26a, it follows that there will be a gradual progression of the movement of the machine over the roadway in a manner entirely similar to that described above.

Obviously the shaft 8c is provided with suitable clutches, similarly as previously described, for controlling the operation and direction of rotation of the conveyer screw positioned in the hopper. These clutches, having been clearly il-

lustrated in Figs. 2, and 3, are not shown in Fig. 8, it being understood that the construction and arrangement of these clutches are identical with the previously described form.

5 Also, there is provided the cam clutch 23b, by means of which the actuation of the cams 27a may be controlled. The cams 27a retain or release rollers 28b and 28c, disposed as described in connection with rollers 28 and 28a, 10 and the cams 27a similarly retain or release the reciprocating sliding arm 10b in the manner previously set forth. This arm 10b is slotted at 30a and reciprocates over the bearing 31a, all as previously described. Therefore the hopper C' oscillates at predetermined time intervals depending upon the relation of the rollers 28b and 28c and the shape of the cam 27a, as described above in connection with the previously 15 described modification; and this rocking motion of the hopper controls of course the reversal of the motion of the machine through the automatic engagement and disengagement of the clutches 39a and 40a responsive to the rocking movements of the hopper. The main clutch 11a is controlled by actuation of the lever 44a, while the lever 47a controls the cam clutch 23b. Suitable levers, not shown, will be understood to be provided for the remaining clutches for controlling the actuation of the distributing 20 screw.

By disengaging this cam clutch 23b the machine may be caused to travel continuously either forward or backward. It will be seen that the cams 27 and 27a are mounted upon sleeves having an enlarged head to prevent lateral movement of the cam and shaft. The enlarged head is indicated at 50.

It may also be desirable to provide instrumentalities for adjusting the height of the machine above the surface of the roadway, so that the hopper may be raised or lowered with respect to the surface on which the traction devices are to run, thereby permitting the obtaining of the paving surface level not on the same level on which the traction devices are to run. It will be seen that the provision of this construction will be desirable particularly where old road surfaces are to be covered with several inches of bituminous macadam to obtain a new wearing surface. It often happens that these old surfaces are sufficiently level so that road forms may not be necessary. In this case the removable flanges on the traction devices are taken off and the hopper raised possibly two or three inches, depending upon the thickness of the material to be applied. The machine can then be operated over the old surface.

For accomplishing this, adjustment mechanism such as illustrated in Figs. 1, 10 and 11 may be provided. It will be understood that this mechanism is adapted for either form of the invention herein illustrated, but it will be described in detail in connection with the modification shown in Figs. 1 and 2.

To incorporate this adjusting mechanism, the shaft 4, instead of being mounted fixedly in the hopper of the machine may be mounted in the block 51 through the instrumentality of a bushing 52. The block 51 is enclosed in a casing 53 mounted on the hopper of the machine, the casing 53 and the side wall of the hopper 53a being provided with an elongated slot 54 in which the bushing 52 is mounted to slide. It will be understood that the block 51 also slides within the casing 53. The block 51 is connected at its

upper end with a toothed rack 55, connection being made by a pin 56, so that the connection between the block 51 and rack 55 is yielding in character. Meshing with the rack 55 is the pinion 57, which is actuated by the gear 58 engaging the threads of a worm 59 provided on the shaft 60. The shaft 60 is connected with a handle 61 by means of universal joint 61a and turning the handle 61, the shaft 60 and worm 59 will be rotated, the pinion 57 actuated, and the rack 55 raised or lowered as the case may be, thereby effecting a corresponding adjustment of the shaft 4 and the hopper C mounted thereon.

The handle 61 may be extended to the operator's position so that the operator can easily and quickly adjust the height of the spreading hopper with respect to the level on which the carrying wheels run. This is especially desirable where an old pavement is to be resurfaced and when the old pavement may vary too much from the desired level. For accomplishing this adjustment under these conditions, any well-known servo-type mechanism may be employed, so that only a slight effort is required on the part of the operator to cause power to operate these adjusting devices at will in either direction and independently of each other. This type of mechanism is well known and is employed in the usual well known manner; therefore it has not been shown in the drawings, nor need it be described in detail herein.

In order to prevent discharge of aggregates from the ends of the hopper, edge blades are provided along each end or side of the hopper, these edge blades not only preventing the aggregates flowing out sideways on to the road forms, but also confining the application of the material to the definite desired width. The mounting of these blades is shown in detail in Figs. 12 and 13, it being understood that the illustrated construction is duplicated at the other end of the hopper not shown in the figures. The blade 62 is mounted on the frame D of the machine to abut against the end of the hopper C and is positioned over the road forms, or the like, 63, 115 being relatively close thereto. The blade is desirably of the shape shown in the figures, and has secured thereto outstanding upper and lower brackets 64 and 65, which are apertured to slidably receive the bar 66, which is of a length 120 sufficient to extend substantially above and below the brackets.

The blade 62 is carried by the carrying members 67 and 68, the former of which is illustrated as being a substantially straight bar bolted to the underside of the frame D, as indicated at 69, and supporting the upper part of the bar 66, while the member 68 is shown as being an angle piece secured to the side of the frame D of the machine by bolts 70 and 71, and being 130 shaped so as to support the lower portion of the bar 66. The bar 66 is held in position by pins, or equivalent members, 72 and 73. Between the carrying member 67 and the lower bracket 65, there is positioned a spring 74, which provides 135 a resilient mounting for the blade as the machine travels along the roadway.

It will be understood that the blades 62 extend completely across the ends of the hopper and upwardly sufficiently far to control any discharge over the road forms at any height of adjustment of the hopper.

It will therefore be seen that by this invention there is provided a machine which will effectively distribute, level, and finish road surfacing 150

materials in substantially one operation, and which will be applicable either to the resurfacing of an old roadway or in the building of a new roadway wherein the surfacing materials are laid upon a newly prepared subgrade.

It is believed that the operation of the machine will be apparent from the foregoing description, and that a detailed description of the operation will accordingly be unnecessary.

10 To load the hopper, trucks containing the surfacing material are backed up along the sub-grade to the forward edge of the newly laid surface. The spreader is then traveled forward to where it is in position to receive the material 15 from the truck and it is then stopped until the truck has discharged its load. Since the spreading screw in the hopper is operated in one direction or the other as may be required to spread the material uniformly in the hopper, the machine consequently will place the material on the sub-grade uniformly. It will be understood 20 that suitable clutches are provided to control the traction devices so that one clutch or the other may be disengaged when the machine has 25 been made to travel around a section of curved roadway. Clutches of the conventional type are used for this purpose.

Having thus described my invention, what I claim as new and desire to secure by Letters 30 Patent of the United States is:

1. In a machine of the character described, in combination, a frame, traction devices carrying the frame, a tilttable distributing hopper mounted on the frame, the said hopper being adapted to 35 distribute surfacing materials upon a roadway, and being provided with instrumentalities movable therewith for working the spread materials, when said hopper is tilted in one direction, and means for levelling the materials when the hopper is tilted in another direction.

2. In a machine of the character described, in combination, a frame, traction devices carrying the frame, a distributing hopper tiltably mounted on the frame and adapted to tilt responsively to travel of the machine along a roadway, and mechanism enabling the hopper to tilt at predetermined intervals, the said mechanism including a reciprocatory arm connected to the hopper, a cam for holding the said arm rigid while releasing the said arm at predetermined 45 intervals to enable the hopper to tilt responsively to the release of the said arm, and instrumentalities for continuously rotating the cam.

3. In a machine of the character described, in combination, a frame, traction devices carrying the frame and enabling the machine to travel along a roadway, a distributing hopper tiltably mounted on the frame for depositing, distributing, and working aggregates on the roadway, and adapted to tilt at predetermined intervals as the machines travel along the roadway, and mechanism for preventing tilting of the hopper between the said intervals while releasing the hopper for tilting at the said intervals.

4. In a machine of the character described, in combination, a frame, traction devices carrying the frame and enabling the machine to travel along a roadway, an aggregate distributing hopper tiltably mounted on the frame and adapted to tilt responsively to travel of the machine along a roadway, and mechanism enabling the hopper to tilt back and forth at predetermined intervals, the said mechanism including a rotatably mounted cam, rollers in engagement with the cam, and an arm interconnecting the hopper

and cam, the cam being of such configuration as to hold the arm and hopper rigidly during a portion of the arc of rotation of the cam, while releasing the arm and hopper during the remainder of the arc of rotation of the cam, thereby enabling the hopper to tilt at predetermined time intervals, and mechanism for rotating the cam.

5. In a machine of the character described, in combination, a frame, traction devices carrying the frame, a distributing hopper mounted on the frame, the said hopper being adapted to distribute surfacing materials upon a roadway and being provided with instrumentalities for leveling and working the spread materials, means enabling the hopper to tilt during the traveling of the machine, and mechanism responsive to the tilting of the hopper for reversing the direction of travel of the machine, the said mechanism including power transmitting devices arranged to propel the traction devices in a forward direction to a somewhat greater extent than in the reverse direction to thereby gradually propel the machine along the roadway as the hopper distributes and acts upon the surfacing materials.

6. In a machine of the character described, in combination, a frame, front and rear traction devices carrying the frame, a distributing hopper tiltably mounted on the frame substantially midway between the front and rear traction devices, and mechanism enabling the hopper to tilt at predetermined intervals during travel of the machine along a roadway.

7. In a machine of the character described, in combination, a frame, traction devices carrying the frame, an oscillatable shaft mounted on the frame, a distributing hopper mounted on the shaft for distributing the road surfacing materials as the hopper oscillates with the said shaft, and a mechanism for adjusting the height of the hopper relatively to a roadway surface being operated upon, the said mechanism including a casing provided with an elongated slot surrounding the said shaft, a bushing for the shaft movably mounted in said slot, a block vertically movable within the said casing and carrying a bushing and shaft, and mechanism for varying the position of the hopper with respect to the shaft.

8. In a machine of the character described, in combination, a frame, traction devices carrying the frame, a distributing hopper mounted on the frame, the said hopper being adapted to distribute surfacing materials upon a roadway, means enabling the hopper to tilt during travel of the machine, a mechanism responsive to the tilting of the hopper for reversing the direction of travel of the machine, said mechanism including a driving shaft, a driven shaft actuated with the traction devices, power transmitting devices for transmitting power from the driving shaft to the driven shaft and including a sprocket on each shaft with interconnecting driving means therefor and intermeshed gears on each of the said shafts, whereby the direction of rotation of the driven shaft may be selectively reversed, and mechanism for alternately actuating the said sprockets and gears responsive to the tilting of the hopper, whereby the direction of travel of the machine over a roadway surface is reversed each time the hopper tilts, the said sprockets and gears being of such relative size so as to cause the machine to advance in a direction somewhat greater than

that of the reversed travel of the machine, whereby the said machine gradually progresses along the roadway.

9. In a machine of the character described, in combination, a frame, a tiltable hopper mounted on the frame, mechanism enabling the hopper to tilt, said hopper being adapted to spread road surfacing materials over a roadway, and being provided with front and rear strike-off blades for leveling the spread surfacing materials, at least one of the said strike-off blades being provided with teeth for digging into the surfacing materials as the hopper oscillates, thereby preventing any tendency of the surfacing materials to bridge over irregularities in the roadway.

10. In a machine of the character described, in combination, a frame, an aggregate distributing hopper, carried by the frame, mechanism for adjusting the height of the hopper relatively to a roadway surface being operated upon, blades abutting the ends of the hopper for preventing discharge of aggregates from the hopper beyond the ends thereof irrespectively of the height of the hopper above the roadway, and means for mounting the blades from the said frame, including vertically disposed brackets on the blades, a bar slidably positioned through the brackets, carrying members secured to the frame and carrying the bar, at the top and bottom thereof, in suitable position relatively to the brackets, and a spring positioned between the top carrying member and the lower bracket to cushion the blade during travel of the machine along the roadway.

11. In combination with a frame having traction devices thereon, a source of power mounted on said frame, power transmitting means associated with the said source of power and said traction devices, control instrumentalities for said transmitting means to couple and uncouple said traction devices with said source, a tiltable hopper mounted on said frame, means for tilting said hopper, instrumentalities associated with said hopper and with said control instrumentalities whereby, when said hopper is tilted, said control instrumentalities are actuated to couple the source of power with said traction devices to move the frame and hence the hopper over a roadway to effect the distribution of surfacing materials contained in the hopper.

12. In combination with a frame having traction devices thereon, a source of power, power transmitting means associated with said source and said traction devices, control instrumentalities for said transmitting means to couple and uncouple said traction devices with said source of power, a tiltable hopper mounted on said frame, having a discharge outlet and adapted to receive surfacing materials and to discharge the same on a roadway, means for levelling the material discharged on the roadway, associated with said hopper, means for tilting said hopper,

comprising instrumentalities operated from said source of power, means on said hopper and connected to said control instrumentalities to couple the traction devices with the source of power when the hopper is tilted, whereby said hopper while discharging is moved over a roadway and said levelling means is caused to level said surfacing materials thus discharged.

13. In combination with a frame and traction devices mounted thereon, a source of power, means for transmitting power from said source to said traction devices, control instrumentalities for said transmitting means for coupling and uncoupling said source of power to said traction devices, a tiltable hopper mounted on said frame adapted to receive surfacing materials and having a discharge outlet for distributing the same to a roadway, a blade on said hopper, means for tilting said hopper, instrumentalities associated with said hopper and said control instrumentalities whereby, when said hopper is moved to tilted position, said blade is brought into engagement with said surfacing materials on the roadway discharged from the hopper, and said control instrumentalities are actuated to move said frame over the roadway and said blade into engagement with said surfacing materials on the roadway to level the same.

14. In combination with a frame having traction devices thereon, a tiltable distributing hopper mounted on the frame for receiving and distributing surfacing material to a roadway, means associated with said hopper for levelling and receiving the materials discharged on the roadway, means for tilting the hopper first in one direction, then in another, to bring said means for levelling and working the material into engagement therewith, and means for moving the frame first in one direction and then in the other to draw the levelling and working means over said materials.

15. In combination with a frame having traction devices thereon, a tiltable hopper mounted on said frame, adapted to receive and discharge surfacing materials upon a roadway, a strike-off blade depending from said hopper, a second strike-off blade spaced from said first strike-off blade and depending from said hopper, means for tilting said hopper to bring one of said strike-off blades into engagement with the materials discharged from the hopper, means for moving the frame in one direction to draw said blade over the materials thus discharged, and means for reversing the direction of travel of the frame when said hopper is tilted in another direction and wherein said second blade is brought into engagement with the surfacing materials and the first blade is removed from engagement with the surfacing materials, to draw said second named blade over the material in a direction reverse of that taken by the first blade.
